UNITED STATES PATENT OFFICE.

HOWARD A. DIEFENDERFER AND WILLIS COOPER HOHL, OF LEHIGHTON, PENNSYLVANIA.

SPINNING MACHINE.

Application filed April 3, 1926. Serial No. 99,636.

This invention relates to improvements in spinning machines, mainly designed for the spinning of silk, the general object of the invention being to provide positive means for driving the spindles, instead of frictional means so as to insure a uniform twist throughout the length of the thread.

Another object of the invention is to provide means whereby the spindle can be easily swung to a position where it will be rendered inactive, with latch means for holding it in this position.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:—

Figure 1 is a fragmentary plan view of a portion of a spinning machine, showing our invention in use.

Figure 2 is a section on line 2—2 of Figure 1.

Figure 3 is a section on line 3—3 of Figure 1.

In these views, 1 indicates the main line drive shaft which is driven from the motor A through the gears 4, this shaft being journaled in the frame 5. The shaft 1 carries a number of beveled gears 6, each of which meshes with a beveled pinion 7 secured to each of the spindles 8. Thus the spindles are positively driven from the line shaft and this will eliminate unequal twisting of the threads which takes place when the spindles are frictionally driven.

Each spindle is rotatably mounted through means of the anti-friction bearings 9, in an arm 10 which is pivotally connected with the frame, as shown at 11, so that the arm can be swung outwardly, by means of its handle 12, to move the gears 6 and 7 out of mesh and thus stop the rotation of the

spindle. A spring pressed plunger 13 in the frame acts to hold the arm in its swung out position, with the gears out of mesh, the plunger being retracted by means of its handle 14 to permit the arm to be moved inwardly to place the gears into mesh again. 50 The arm is held in operative position by means of the coiled spring 15 which is connected with the arm and with a part of the frame and an adjustable stop is provided for the arm which consists of a set screw 17 on a part of the frame having its end engaged by the arm when said arm is moved inwardly by the spring. The spring, holding the arm against the stop, will properly position the pinion 7 in relation to the gear 6 to cause the gears to mesh so that the movement of the line shaft will be communicated to the spindle. When the spindle needs attention from the operator, he simply grasps the handle and swings the 70 arm outwardly to uncover the plunger, when the spring of the plunger will project it and thus hold the arm in its outward position with the gears out of mesh. After the spindle has been finished with, the operator retracts the plunger, so as to permit the spring 15 to return the arm to operative position and to cause the pinion to mesh with the gear. 75

Thus we have produced simple means for 80 positively driving the spindles, with means for permitting the spindles to be freed of the driving means whenever desired.

It is thought from the foregoing description that the advantages and novel features 85 of our invention will be readily apparent.

We desire it to be understood that we may make changes in the construction and in the combination and arrangement of the several parts, provided that such changes fall 90 within the scope of the appended claims.

What we claim is:—

1. In a spinning machine, a line shaft, a gear thereon, an arm pivoted to the frame of the machine, a handle on the arm, a spindle rotatably supported by the arm, a gear thereon meshing with the beforementioned gear, latch means for holding the arm with 95

the spindle gear out of mesh with the other gear and a stop for holding the arm in a position with the gears in mesh.

2. In a spinning machine, a line shaft, a gear thereon, an arm pivoted to the frame of the machine, a spindle rotatably supported by the arm, a gear on the spindle engaging with the first mentioned gear, a spring latch for holding the arm in a position with

the gear on the spindle out of mesh with the other gear, an adjustable stop for holding the arm with the gears in mesh and a spring connected with the arm for holding the same against the stop.

In testimony whereof we affix our signatures.

HOWARD A. DIEFENDERFER
WILLIS COOPER HOHL.
